UNITED STATES PATENT OFFICE.

JOHN THOMAS MALLARD, OF RALEIGH, NORTH CAROLINA.

SAFETY FASTENER FOR SLIDING DOORS.

1,403,178.

Specification of Letters Patent. Patented Jan. 10, 1922.

Application filed March 9, 1921. Serial No. 450,851.

To all whom it may concern:

Be it known that I, JOHN THOMAS MALLARD, a citizen of the United States, and resident of Raleigh, in the county of Wake 5 and State of North Carolina, have invented certain new and useful Improvements in Safety Fasteners for Sliding Doors, of which the following is a description, reference being had to the accompanying drawings, 10 which form a part of my specification.

My invention relates to improvements in safety fasteners for sliding doors, more particularly to the doors of railway baggage and express cars, and it also is applicable to 15 various other types of sliding doors where it is desirable to prevent undue closing of the same.

The wide side openings of railway baggage and express cars are provided with 20 sliding doors the sudden undue closing of which frequently causes serious accidents to messengers and baggagemen standing in the open door-ways when trains approach a station and are brought to a sudden stop 25 causing the door to close suddenly, and which also occurs from other causes incidental to the operation of railway cars.

The object of my invention is to provide a device for attachment to the door, where- 30 by the latter when open cannot be closed except by manipulating a lever which in turn operates a stop bolt adapted to engage perforations or receptacles therefor formed in the door frame or in a strip of iron or other 35 material secured thereto.

With the aforesaid and other objects in view the invention consists in the various novel details of construction and combination of parts hereinafter fully described in 40 the specifications, illustrated in the drawings and more particularly pointed out in the claims.

In the accompanying drawings forming part of the specification, and in which like 45 reference numerals indicate corresponding parts, I have illustrated one form of device embodying the essential features of my invention, although the same may be carried into effect in other ways without in the least departing from the spirit thereof.

In the said drawings Figure 1 is a reduced front view of the device applied to a door, the face member of the bolt casing and the door sheave being shown as a single 55 structure and the door partially open.

Fig. 2 is a similar view to Figure 1 show-

ing the bolt casing and the door sheave as separate units, the door being shown closed.

Fig. 3 represents a broken perspective view of the bolt casing separated from the door sheave and detached from the door, showing the lock bolt and its operating lever in their relative positions and a keeper-plate located thereabove, the latter being partly in longitudinal section in which an incline is 65 shown adjacent to the bolt aperture.

Fig. 4 is a vertical cross section, taken on the line $z z$ of Figure 1, looking toward the front end of the car, showing a modified form of door track in which stop perforations are formed in the horizontally disposed member thereof.

Fig. 5 is a vertical cross section taken on the line $A A$ of Figure 2, looking toward the front end of car.

75

Fig. 6 is a longitudinal section through the center of the lock bolt casing showing a part of the operating lever and its pivotal connection with the casing.

It is to be noted that for the purpose of 80 this application my invention is illustrated and described in connection with the sliding door of an express car, one side of which is denoted by the numeral 1. 2 represents the side door opening and 3 the door, which 85 is usually hung on a pair of door sheaves 4—one only being shown—the rollers 5 of which traverse a track 6 secured to the car above the door opening, and shown also, in modified form, at 7 in Figures 1 and 4, it is 90 to be understood, however, that my invention does not contemplate the use of any particular form of door track nor of any special type of door sheave and that it may be used in conjunction with any suitable 95 form or type of either. 8 represents a lock bolt casing comprising two rimmed sections 8¹, 8² secured together by screws 9, 10, or they may be secured by any other convenient or desirable means, the face member of sec- 100 tion 8¹ is provided with end extensions 8³, 8⁴ adapted to receive screws for securing the casing in place. Within the chamber thus formed there is located a lock bolt 11 bifurcated and pivotally connected at one end 105 with an operating lever 12 by means of pintle 13, the lever 12 being pivotally connected with the casing 8 by means of a pintle 14 which may be formed integral with one of the casing sections or it may be a separate 110 piece secured to the casing section as more clearly shown in Figure 6, or any other suit-

able means may be employed for pivotally connecting the lever with the casing. The lever 12 is bent, at 15 and 16, to form an angle section 17 thereof which operates in a curved slot or opening 18 in the face member of section 8¹ of the casing, so that one part of the lever operates within the casing and the other part operates on the outside thereof, as best shown in Figure 3.

10 The upper rim of the casing 8 is provided with an aperture or bore 19 to receive the lock bolt and in which the latter has vertical movement, the purpose of which will presently appear. The casing is recessed 15 into the side of the door, adjacent to its top horizontal edge and at suitable distance from the vertical edge thereof, so that the face of the casing will be flush with the side of the door. A stop strip or keeper-plate 20 of suitable material is secured to the underside of the door opening lintel and may comprise a separate unit, indicated by the numeral 20 in Figures 2 and 5, or it may consist of an integral member of the 25 door track as indicated by the numeral 21 in Figure 4, in either case the keeper is perforated, as at 22, to receive the free end of the lock bolt 11 and when so engaged the door is held against undue movement in 30 either direction, it being obvious that any desired number of such engagement may be provided for, also that when the door is closed and the parts referred to are in engagement a separate lock for the door may 35 be dispensed with, entrance to and exit from the car being had through its end doors.

The free end of the operating lever 12 is pivotally connected, at 23, with the bifurcated end of an operating bar 24, the opposite end of which terminates in a handle 25 whereby the bar may be raised and the upward movement of which operates the lever 12 which in turn lowers the lock bolt 11 thereby releasing it from engagement with 40 the perforation 22 in the keeper-plate and permitting of unobstructed movement of the door, the weight of the operating bar, when unrestrained, serving to force the lock bolt into the perforations when their relative positions permit of engagement therewith.

To make more positive and to insure engagement of the lock bolt with the perforations in the stop strip or keeper-plate as the door moves forward towards a closing 55 position inclines 26, see Figure 3, are formed in the said stop strip or keeper-plate at each perforation, up which inclines the end of the lock bolt travels and is halted by the opposite wall of the perforation, thus avoiding failure to perform its intended function.

The operating bar is held in position by guide members 27—28 secured to the door and in which said bar is free to move in a vertical line, its movement being limited by 60 the said guide members.

Reference has been made to a curved slot or opening 18 formed in the face member of the section 8¹ of the casing, also to an aperture or bore 19 to receive the lock bolt formed in the upper rim of the casing while 70 two such slots and two such apertures are shown in the drawings, the purpose for which the casing is provided with these additional openings, indicated by the numerals 29 and 30 respectively, is that the 75 device may be adaptable for use on either right or left hand doors by simply mounting the operating lever 12 so that it and the lock bolt will operate in whichever set of 80 said openings may be necessary to adapt the device to a right or a left hand door as the case may be, thus contributing to expediency, economy and convenience in manufacture by avoiding the necessity of separately 85 constructing the device for right and left hand doors.

In Figures 1 and 4 of the drawings the front section 8¹ of the lock bolt casing and the face or supporting member 4¹ of the door sheave is shown as comprising a single unit, 90 preferably a casting, and in Figures 2, 3 and 5 the door sheave and the lock bolt casing are shown as separate units.

While my invention per se is separate and distinct from and does not necessarily involve the use of any particular type of door sheave yet, where it is to be applied to new doors or to doors not previously mounted combining of the face or supporting member of the door sheave with the face or front 100 section 8 of the lock bolt casing in a single unit contributes economy and convenience in manufacture, as well as in the application of the device to a door.

In the particular embodiment of my invention shown in the drawings, when the lock bolt is engaged with one of its coating stops, or perforations, the door is held against movement in either direction and the operating bar is at rest at its lowest limit of travel and raising of the bar to its highest limit of travel withdraws the lock bolt from such engagement and permits of free movement of the door in either opening or closing direction.

It is obvious that my invention is equally well adapted to cars of wood or steel construction or of a combination of wood and steel; and that details of construction as herein shown and described may be departed 110 from in various particulars without in the least departing from the spirit of my invention.

I claim:—

1. In a safety fastener for sliding doors, 115 the combination with a door of a casing adapted to be secured to the door, one or more stops secured to a support above said casing, an operating lever pivotally mounted on said casing, a lock bolt in pivotal con- 120

- nection with one end of said lever and whose free end is normally in position to automatically engage the said stops during travel of the door, and a vertically disposed movable bar in operative connection with the opposite end of said lever; whereby raising of said bar will rock said lever causing withdrawal of said lock bolt from engagement with the stop and permit of unobstructed movement of the door while the said bar is in a raised position.
2. In a safety fastener for sliding doors, the combination with a door of a casing adapted to be secured to the door, a keeper-plate secured to a support above said casing having one or more stop openings therein, an operating lever in pivotal connection with said casing, a lock bolt operative within and through said casing and being in pivotal connection with one end of said lever and whose free end is normally in position to automatically engage the said stops during travel of the door, a vertically disposed movable bar in operative connection with the opposite end of said lever; whereby raising of said bar will rock said lever causing withdrawal of said lock bolt from engagement with the stop opening and permit of unobstructed movement of the door while said bar is in a raised position, and guide members secured to the door for controlling the vertical movement of said bar.
3. In a safety fastener for sliding doors, the combination with a door of a casing adapted to be secured to the door, a lock bolt operative within and through a rim of said casing, an operating lever in pivotal connection with said bolt and with said casing, a keeper-plate located above said casing having one or more stop openings adapted to receive the free end of said lock bolt, an inclined surface leading from substantially midway of the depth of the opening to the bottom side of the keeper-plate and up which inclined surface the end of the lock bolt travels to engage the opening, and means connected with said lever for operating the lock bolt by the movement of said lever.
4. In a safety fastener for sliding doors, the combination with a door of a casing adapted to be secured to the door, a lock bolt operative within and through a rim of said casing, an operating lever in pivotal connection with said bolt and with said casing, a keeper-plate located above said casing having one or more stop openings adapted to receive the free end of said lock bolt, an inclined surface leading from substantially midway of the depth of the opening to the bottom side of the keeper-plate and up which inclined surface the end of the lock bolt travels to engage the opening, and a vertically disposed movable bar in operative connection with the opposite end of said lever adapted by a lifting movement thereof to rock said lever and release said lock bolt from locking engagement with said keeper-plate.
5. In a safety fastener for sliding doors, the combination with a door of a casing adapted to be secured to the door, a lever pivotally mounted on said casing, a lock bolt in pivotal connection with one end of said lever, a keeper-plate provided with stop-openings secured to a support above said casing; said openings being adapted to receive the free end of said lock bolt, and a movable bar in operative connection with and depending from the opposite end of said lever whereby the weight of said bar will cause the free end of said lock bolt to automatically engage said stop-openings and when held in raised position will disengage said bolt therefrom and permit of unobstructed movement of the door.
6. In a safety fastener for sliding doors, the combination with a door of a casing adapted to be secured to the door, a lever pivotally mounted on said casing, a lock bolt in pivotal connection with one end of said lever, a keeper-plate provided with stop-openings secured to a support above said casing; said openings being adapted to receive the free end of said lock bolt, a movable bar in operative connection with and depending from the opposite end of said lever whereby the weight of said bar will cause the free end of said lock bolt to automatically engage said stop-openings and when held in raised position will disengage said bolt therefrom and permit of unobstructed movement of the door, guide members secured to the door for controlling the vertical movement of said bar, and a handle formed on said bar whereby the same may be operated.
7. In a safety fastener for sliding doors, the combination of a casing adapted to be secured to a door and having a slot or opening through the outer face thereof, an operating lever comprising two parallel off-set sections, formed by an angular section therebetween; one of said parallel sections being pivoted to and within said casing and the other being disposed outside thereof; the said angular section being operative in said slot or opening, a lock bolt in pivotal connection with the end of said lever within said casing, a keeper-plate secured to a support above said casing having provision for receiving the free end of said lock bolt to arrest movement of the door, and means connected with the opposite end of said lever whereby said lock bolt may be withdrawn from locking engagement with said keeper-plate.
8. In a safety fastener for sliding doors, the combination of a casing adapted to be secured to a door and having a slot or open-

ing through the outer face thereof, an operating lever comprising two parallel off-set sections formed by an angular section therebetween; one of said parallel sections being pivoted to and within said casing and the other being disposed outside thereof; the said angular section being movable in said slot or opening, a lock bolt in pivotal connection with the end of said lever within 10 said casing, a keeper-plate secured to a support above said casing having stop-openings for receiving the free end of said lock bolt to arrest movement of the door, a movable bar in operative connection with and depending from the opposite end of said lever; 15 whereby the weight of said bar will cause

the free end of said lock bolt to automatically engage said stop-openings and when held in raised position will disengage said bolt therefrom and permit of unobstructed 20 movement of the door, guide members secured to the door for controlling the vertical movement of said bar, and a handle formed on said bar whereby the same may be operated.

In witness that I claim the foregoing I have hereunto subscribed my name this 1st day of March, 1921.

JOHN THOMAS MALLARD.

Witness:

R. T. HAMLET.
